[57] CLAIM

The ornamental design for an easel for attaching to a telephone to support a book or the like, substantially as shown and described.

DESCRIPTION

FIG. 1 is a prospective view of the front and one side of the easel for attaching to a telephone to support a book or the like;

FIG. 2 is a view from one side thereof, the opposite side thereof being a mirror image of that shown;

FIG. 3 is a front view thereof; and

FIG. 4 is a back view thereof.

*FIG. 1**FIG. 2**FIG. 3*

FIG. 4
